ATTORNEY

UNITED STATES PATENT OFFICE.

LLEWELLYN B. SHULTZ, OF ST. LOUIS, MISSOURI, ASSIGNOR TO PILLEY PACKING & FLUE BRUSH MANUFACTURING COMPANY, OF ST. LOUIS, MISSOURI, A CORPORATION OF MISSOURI.

ROTARY ABRADING BRUSH.

Application filed June 15, 1922. Serial No. 568,409.

To all whom it may concern:

Be it known that I, LLEWELLYN B. SHULTZ, a citizen of the United States of America, residing at the city of St. Louis, 5 State of Missouri, United States of America, have invented a certain new and useful Rotary Abrading Brush, of which the following is such a full, clear, and exact description as will enable anyone skilled in 10 the art to which it appertains to make and use the same, reference being had to the accompanying drawings, forming part of this specification.

My invention relates to a rotary abrading brush suitable for removing carbon from the cylinders of internal combustion engines, for removing paint and rust from iron structures, and other similar purposes.

One object of my invention is to provide 20 simple and effective means for varying the stiffness of the brush. Another object of my invention is to so form the brush that the pressure of the working face against the article operated upon will tend to equalize 25 the stiffness of the wires throughout the area of the working face. Another object of my invention is to provide means for readily renewing the wire portion or tuft of the brush.

In the accompanying drawings which illustrate one form of brush made in accordance with my invention, Figure 1 is a side elevation, Figure 2 is a longitudinal central section, and Figure 3 is a section 5 taken on the line 3—3 of Figure 2.

5 indicates a cylindrical core or plug in one end of which is suitably secured a steel shank 6 by means of which the brush may be secured in an actuating chuck, as for example, the chuck of a drill press, or a chuck carried by a flexible shaft so that the brush may be used as a hand tool. The exterior of the plug 5 is screw threaded to cooperate with corresponding screw threads on the interior of a sleeve 7, which sleeve operates to vary the stiffness of the brush as will be hereafter more fully pointed out.

The plug 5 is provided with a central aperture 8, the lower end of which is threaded to receive the upper threaded end 9 of a stem or support 10. This stem 10 is composed of a plurality of rods, preferably four in

number, twisted together with interposed steel wires 11. This structure provides a conical abrading tuft, the wires of which 55 progressively increase in length from the center to the periphery. The working end of the tuft 11 is formed to be normally concave as shown in Figure 2 of the drawings.

The operation of my brush is as follows: 60

The brush is actuated by being held in any suitable rotating chuck and the concave face 12 is forced against the article to be abraded. Owing to the form of the face the outer wires will come in contact with the surface 65 to be abraded before the inner wires and consequently the outer wires will be bent so that these wires, which are longer and naturally more flexible than shorter wires, will have their tension increased to more 70 evenly distribute the abrading effect throughout the entire working face of the brush. By moving the sleeve 7 longitudinally which is accomplished by rotating it, the angle of the tuft 11 and the consequent 75 stiffness of the brush as a whole can be varied to accommodate the brush to the particular class of work to which it is to be applied. I find that the contact of the inner lower edge of the sleeve with the tuft 11 80 effectively prevents accidental rotation of the sleeve after the adjustment has been made and consequently no additional locking means is necessary. When the tuft 11 becomes worn it may be renewed by simply 85 unscrewing the stem 10 from the aperture 8 and substituting a new tuft.

Having fully described my invention what I claim as new and desire to secure by Letters Patent of the United States is:

1. In a rotary abrading brush, the combination with a stem consisting of a plurality of rods twisted together, of wires interposed between said rods and forming a conical abrading tuft, the end of said tuft being 95 normally concave and means for varying its degree of concavity and consequently the working pressure of the brush.

2. In a rotary abrading brush, the combination of a plurality of rods twisted together 100 with interposed wires forming a conical abrading tuft, said tuft having a normally concave working end, of a threaded sleeve for compressing said tuft to vary the angle

of convergence of the sides of the tuft and the consequent working pressure of the brush.

3. In a rotary abrading brush, the combination with a plug having a central opening and threaded exteriorly, of a conical wire brush provided with a stem secured in the central opening of said plug, an in-

teriorly threaded sleeve adjustable along said plug and bearing upon the brush to ¹⁰ vary its conical angle, and a shank carried by said plug securing the device in a driving chuck.

In testimony whereof, I have hereunto set my hand and affixed my seal.

L. B. SHULTZ. [L. s.]
